UNITED STATES PATENT OFFICE.

RALPH H. HOLMAN, OF STONEHAM, AND FRANCIS D. SHENK, OF MEDFORD, MASSACHUSETTS, ASSIGNORS TO THE LEGALITE CORPORATION, OF BOSTON, MASSACHUSETTS, A CORPORATION OF MASSACHUSETTS.

HEADLIGHT.

1,331,813.

Specification of Letters Patent. Patented Feb. 24, 1920.

Original application filed December 16, 1915, Serial No. 67,105. Divided and this application filed September 20, 1916. Serial No. 121,296.

To all whom it may concern:

Be it known that we, RALPH H. HOLMAN and FRANCIS D. SHENK, citizens of the United States, residing at Stoneham, county 5 of Middlesex, Commonwealth of Massachusetts, and Medford, county of Middlesex, Commonwealth of Massachusetts, have invented certain new and useful Improvements in Headlights, of which the following is a specification.

This invention relates to headlight screens and particularly to the arrangement of prismatic elements of such a screen adapted to deflect light from the theoretically parallel beam of a headlight reflector to depress the same below the "glare" level and to distribute the light satisfactorily along the roadway, being in effect a division or continuation of application, Serial No. 67,105, filed Dec. 16, 1915, now Patent No. 1,224,421, issued May 1, 1917. We accomplish this object generally by an arrangement of transverse prisms on the glare screen which forms the front of a headlight, 15 treating the upper part of the beam with series of prisms, the angles of which have a progressively increasing depressor function from the top toward the center and treating the lower part of the beam with 20 series of prisms having angles decreasing from the center toward the bottom, so that that portion of the upper part of the beam lying nearest the center and of the greatest area is more depressed than the 25 small area of the upper edge while the lower part of the beam is treated in the reverse manner. The central prisms are preferably of a uniform small angularity. We secure in this manner maximum neutralization of 30 the tendency of the lamp to glare and at the same time secure a very uniform illumination of the roadway.

The construction and operation of our device will be more fully described in the 35 specification which follows and an illustrative embodiment is shown in the accompanying drawing, in which

Figure 1 is a front elevation of a prismatic screen,

Fig. 2 is a central section through a lamp 50 equipped with the same, and

Fig. 3 is a central vertical section through a screen.

In the form of our invention herein illustrated, we provide a lamp of the usual type 55 consisting of a shell 1 and a bulb 2 with a screen 3. The screen 3 consists of a circular glass disk provided with means for lateral light distribution and having on its rear face a series of transverse horizontal 60 prisms. Beginning at the upper edge of the lamp where the first prism is short, we make the succeeding prisms of slightly increasing angularity, for example, the first six prisms beginning at the top are respectively of 5, 6, 6½, 7, 7½ and 8 degrees. The corresponding six prisms at the lower face of the screen are decreased from the center downward so that the short prism at the bottom is again a 5 degree prism, the 70 next above it is 6 and so on in reverse order to the top series thus again giving a maximum depressor function to the long prism adjacent the middle portion of the light beam.

We find that the central portion of the light beam is more uniform and its glare tendency more easily controlled. We therefore leave the four central prisms of uniform angularity and of minimum deflector 80 function. For this purpose 5 or even less degrees is sufficient. The exact degree of angularity of any of the prisms may be varied, but we find it particularly advantageous to have the upper and lower portions of the screen reversed in the progressive angular function of the prisms so as to have a suitable control of the brighter parts of the beam where glare is more likely to occur and at the same time give a distribution which will be approximately uniform 85 from adjacent the lamp to the farthest point necessary to be illuminated.

What we therefore claim and desire to 90 secure by Letters Patent is:

1. A refractive screen for a headlight, comprising a body portion and a series of transverse prismatic elements in the upper

and lower portions thereof having an oppositely progressive angular gradation relative to each other, and an intermediate zone of transverse prisms of uniform angularity.

- 5 2. A refractive screen for a headlight, comprising a body portion, and a series of transverse prismatic elements of an angularity increasing from the top toward the center and decreasing from the center to-

ward the bottom, and an intermediate zone 10 of transverse prisms of uniform angularity.

In testimony whereof we affix our signatures in presence of two witnesses.

RALPH H. HOLMAN.
FRANCIS D. SHENK.
